UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

1,414,310.

Specification of Letters Patent. Patented Apr. 25, 1922.

Application filed September 2, 1920. Serial No. 407,672.

To all whom it may concern:

Be it known that I, ARTHUR W. SMITH, citizen of the United States, and resident of the borough of Manhattan, city of New York, in the county of New York and State of New York, have invented certain new and useful Improvements in Typewriting Machines, of which the following is a specification.

10 My present invention relates to carriage feeding or escapement devices for typewriting machines, and its main object is to provide new and improved devices of the character specified and which are more particularly adapted to cure defects heretofore encountered in the operation of the space bar or key.

To the above and other ends my present invention consists in the features of construction, combinations of devices and arrangements of parts hereinafter described and particularly pointed out in the claims.

In the accompanying drawings illustrating the preferred form of my invention, 25 Figure 1 is a fragmentary front to rear vertical sectional view of a typewriting machine embodying my invention.

Figure 2 is a corresponding fragmentary view on a reduced scale and showing the 30 forward portions of a printing key lever and the space bar mechanism.

Figure 3 is a fragmentary front elevation, on an enlarged scale, of the dog rocker or carrier and the dogs mounted thereon, and 35 showing the normal relationship of the dogs with the escapement wheel.

Figure 4 is a horizontal sectional view taken on a plane indicated by the dotted line *w w* in Figure 3 and looking downward.

40 Figure 5 is a view corresponding to Figure 3 but showing the parts as related when the dog rocker is rocked forward by an operation of one of the printing keys.

Figure 6 is a fragmentary horizontal sectional view taken on a plane indicated by the dotted line *xx* in Figure 5 and looking downward.

45 Figure 7 is a view corresponding to Figure 3 but showing the parts as they appear under operation of the space bar.

Figure 8 is a fragmentary horizontal sectional view taken on a plane indicated by the dotted line *yy* in Figure 7 and looking downward.

55 Figure 9 is a fragmentary vertical section-

al view taken on a plane indicated by the dotted line *zz* in Figure 3 and looking rightward as indicated by the arrow at said line.

Referring first to Figs. 1 and 2, the main frame of the machine comprises a base 1 from which rise posts 2 supporting a top plate member 3. Above the top plate is arranged for reciprocation a roller platen 4 mounted on a carriage 5, only a fragment of which is shown, but said carriage may be of any desired construction as may be the connections from said carriage to the escapement wheel or rack member 6, said wheel being supported on a shaft 7 which bears in a bracket member 8. The shaft 7 at its front end carries a feed pinion 9, which meshes with a feed rack 10 mounted on the carriage 5. Adapted to co-operate with the front face of the platen 4 is a set of type bars 11 arranged in an arc below the platen and pivoted on a common fulcrum wire 12, which is mounted on an upright type bar support or segment 13. The type bars are normally horizontally disposed, their forward end portions resting on a pad or rest 14 and being adapted to be actuated to print by devices co-operative with a cam slot 15 formed in the rear or heel portion of each type bar, said devices comprising a headed pin 16 engaging in said slot and projecting laterally from the upwardly extending arm of an angular lever 17 having a stationary pivot 18 and being pivotally connected at 19 with a printing key lever 20 fulcrumed on a fulcrum bar 21 in the rear of the base and provided at its front with an upstanding stem portion 20^a which bears a key cap or button 22. Each printing key lever is provided with a restoring spring 23 which restores it and the connected train of printing devices after the printing key 22 has been actuated to cause its type bar to print. The type bars 11 perform the further function of actuating the carriage feeding or escapement devices and to this end each type bar is formed forward of its pivot with a contact edge or face 24 which is adapted to co-operate with the front edge of an arc-shaped universal bar member 25 vertically disposed behind the type bar segment 13 and normally housed in a seat or depression 26 formed in the rear of the segment member. The universal bar member 25 is provided with a guide pin 27 engaging in an opening 28 in the segment member and is also provided with rearward

extensions or arms 29 which are pivotally connected with a rocking frame comprising a rock shaft 30 and three upstanding arms, the arm shown in full in Figure 1 being the 5 central arm 31, the two end arms 31^a being pivotally connected at their upper ends to the horizontal arms 29 of the universal bar frame. The rocking frame is supported on brackets or lugs 32 depending from the top 10 plate. The central arm 31 carries a cross pin 33 which is engaged by a slot 34 formed in the forward end of a horizontal link or connector 35, the rear end of said link being formed with a slot 36 for co-operation with 15 a headed pin or stud 37 projecting laterally from the downwardly extending operating arm 38 of a dog carrier or rocker designated as a whole by the numeral 39. The details of the universal bar construction, the dog 20 rocker per se and the connections between the two preferably are like the corresponding parts disclosed in the patent to George A. Seib No. 1,289,934, dated Dec. 21, 1918. There must however in the present case be 25 enough space or lost motion between the stud 37 and the end of the slot 36 to permit the dog rocker swing to be reversed without being blocked by the link 35. This can be done and still have enough motion transmitted 30 from the link to operate the rocker in ordinary or direct letter feeding. The dog rocker comprises a body or cross portion 40 and an upstanding plate or arm 41 terminating in a cross head 42. The ends of the body 35 portion 40 are formed with depressions or seats to receive coned bearing pins 43 secured in a bracket or support 44 depending from the top plate. The bracket 8 is mounted on the bracket 44 at its upper side.

40 Stated generally the novel features of my present invention reside in the escapement dogs that are mounted on the rocker or carrier and their manner of co-operation with the escapement wheel or circular rack. 45 There are three of these dogs and the dog rocker is so maintained normally that the middle dog is engaged with the escapement wheel, the rocker being swingable or movable in opposite directions from its central 50 position in order to cause one or the other of the two outside or terminal dogs to co-operate with the escapement wheel. In one direction the movement of the rocker is caused by actuation of the printing keys and results 55 in what is called a direct or "ordinary" feed, that is one whereby the carriage is letter spaced during the return or upstroke of the printing keys. On the other hand, reversing the movement of the rocker or causing it to 60 swing in the opposite direction from its central position, which movement is controlled by actuation of the space bar or key, results in a "reverse" or full drop escapement action; that is, one whereby the carriage 65 is fed during the depression or initial

movement of the space bar or key. The carrier or rocker and the devices for moving it alternatively in opposite directions provide means for selectively determining which pair of the set or plurality of dogs shall be 70 employed. The main purpose of my novel escapement mechanism is to prevent that defect in typewriting which is commonly called a "spread," by which is meant the striking of the first character of a word at 75 the point or place on the paper which should be a space. The difficulty does not arise directly from the action of the printing keys in connection with a direct or no drop escapement but is attributable largely to the 80 fact that the space bar mechanism in a direct feed escapement is inherently slow because of the yielding of the parts and of the fact that operators are not so speedy with the thumb as with the fingers, and it is 85 with the thumb that the space bar is usually actuated. The result is that liability to produce "spreads" in typewriting is quite prevalent and likelihood of doing so is increased by reason of the fact that there is a 90 common tendency on the part of operators to dwell or protract the stroke of the space bar. In my invention the prevention of "spreads" 95 is accomplished by causing the space bar to actuate the escapement mechanism to produce a full drop or "reverse" feed so that the carriage is letter spaced during the down stroke of the space bar. Furthermore the space bar may be held depressed at the end 100 of its down stroke without interfering with the subsequent operation of a letter feed key to produce a direct or no-drop, or, as it is sometimes called "ordinary" feed.

Coming now to the detailed description of the escapement dog mechanism, as best 105 shown in Figs. 1, 3 and 4, the rearmost or back terminal dog member comprises a curved plate 45 provided with slots 46 which receive screws 47 by which the plate is adjustably secured to the rear of the cross head 110 42 of the rocker. The plate 45 has an upstanding finger portion terminating in a forwardly bent end 48 which is the rear dog or holding dog, the forward inclination of the end giving the effect of a bevel action 115 to this rear dog. In front of the rocker plate 41 is arranged a middle or central dog member 49 which, as shown in Figs. 1, 3 and 4, is in the form of an elbow or angular piece comprising an upright arm 50 and a horizontally disposed arm 51, a dog member being pivoted at the junction of the two arms on a headed pin or screw 52 projecting rearward from the forepart of the rocker plate 41. Normally the rocker is so maintained that the dog tooth or upper end portion of the arm 50 of the middle dog is engaged by one of the teeth of the escapement wheel 6 at the bottom or lower side of 120 said wheel. The wheel constantly tends to 125 130

turn in the direction of the arrow in Fig. 3, due to the action of the carriage motor or spring drum, not shown, which is transmitted through the carriage rack 10, feed pin 9 and shaft 7 to the escapement wheel. Through the action or pressure of the engaged escapement wheel tooth the dog 49 is normally held at the rightward limit of its movement which is determined by the 5 engagement of the dog arm 50 with the straight face of a lug or stop 53 projecting rearward from the cross head 42. The arm 50 is provided with a rearwardly extending pin 54 which acts as a stop to limit the leftward swing or stepping movement of the dog 49 under the impulse of the dog spring 55, which is a coiled spring hooked at its lower end over a pin 56 projecting from the tail or horizontal arm 51 of the dog, the 10 upper end of said spring being anchored to a pin 57 projecting from the cross head 42. The forward or front terminal dog, designated as a whole by the numeral 58, comprises an upstanding arm 59 and a lower 15 angularly disposed arm or tail 60, said dog being provided with a hub 61 which is perforated to fit over the pin or stud 52 on which the dog 58 bears forward of the dog 49, the dog 49 being loosely confined between 20 the dog 58 and the front face of the rocker plate 41. The pin 52 must project considerably from its support and in order to hold it firmly the dog rocker is provided at its front side with a boss or projection 52^a 25 which is perforated to receive the pin 52 which is secured by a set screw 52^b (Figs. 3 and 9). A coiled dog spring 62 connected to the tail 60 of the dog 58 and anchored to a pin 63 on the cross head 42 tends constantly to maintain the face of the arm 59 30 in engagement with a stop 64, this stop being in the present case a washer of fiber or the like arranged on the rearwardly projecting end of one of the screws 47 and held in place thereon by a nut 65. The stop pin 54 on the dog 49 is adapted to act against the righthand edge or face of the arm 59 of the forward dog. In order to maintain it in its normal or central position with the 35 middle dog 49 engaged with the escapement wheel, the dog rocker is provided with a spring 66 (Fig. 3) which constantly urges it forward, said spring being anchored to a stationary pin 72 on the bracket 44 (Fig. 4). The forward swing of the rocker is limited by stop devices comprising a screw stop 67 threaded through the rocker below its 40 pivotal axis and projecting forward to operate with the head 68 of a screw pin, stop or plunger 69, which is arranged in a horizontal seat or depression 70 formed in the head or enlargement 71 at the lower end of the stationary arm or bracket member 44. The bottom or left-hand end of the depression 70 is perforated to afford a passage 45 for the leftwardly extending end of the plunger stop 69, this left-hand end portion being threaded to receive a nut 73. A coiled spring 74 surrounds the plunger 69 within the depression 70 and is confined between the head 68 of the plunger and the bottom of the depression. The tendency of the plunger spring is constantly to force the plunger head 68 rearward to the limit of its movement which is determined by the 50 co-operation of the nut 73 with the front wall of the arm 44. The plunger spring 74 is stronger than the rocker spring 66 so that ordinarily the spring plunger serves in effect as a fixed stop co-operating with the stop 67 to limit return movements of the dog rocker following actuation of the printing keys, which operate to swing the upper end of the dog forward to cause the bevel dog 48 in co-operation with the escapement 55 wheel and the middle dog to afford "ordinary" or no-drop feed. The purpose of making the stop head 68 yieldable or movable is to enable it to be overcome so that the upper end of the dog rocker may be 55 swung rearward from its central position to bring the front dog 58 into operation for the purpose of causing a reverse or full drop feed, this result being brought about by the operation of the space bar mechanism. To this end a tail piece or downwardly and forwardly inclined finger 75 is secured to the face of the dog rocker as by a rivet 76, the upper end of the finger being cut out to fit partly around the boss or 60 projection 52^a at the front side of the dog rocker. The finger 75 is acted against by a part operated from the space key as herein-after described. The space key or bar in the present instance is a cross bar 77, Figs. 1 and 2, which connects the forward angular ends 78 of two spacing levers 79 arranged at opposite sides of the machine and provided at their rear ends with downwardly extending portions 79 suitably fixed to a rock shaft 81 supported from the sides of the base frame of the machine. The space bar frame, comprising the rock shaft 81, levers 79 and bar or space key 77, is limited in its movements by a stationary 85 stop finger 82 projecting rearward from the front of the base to which it is suitably secured. The stop finger 82 co-operates with stops 83 and 84 on the space bar 77, these stops preferably being the parallel angularly 90 disposed ends of a plate or piece 84^a suitably fixed to the under side of the space bar 77. Projecting rearward and upward from the rock shaft 81 to which it is suitably secured, is a centrally arranged arm 85 on which is 95 pivotally supported at 86 an extension or second arm 87 that also inclines upward and rearward; its free end underlying the finger 75 against which it is adapted to act. The tail of the arm 87 or, considering the part 100 105 110 115 120 125 130

a lever its shorter arm is provided with a lateral pin 88 over which is hooked a coiled spring 89, the lower end of said spring having a stationary anchorage 90. This spring 5 acts to maintain a cut-out 87^a formed in the arm 87 in engagement with a lateral stop pin 91 projecting from the upper end of the arm 85. The construction permits the upper end portion of the arm 87 to be swung downward about the pivot 86 as a center and independently of the arm 85, this swinging movement being in opposition to the spring 89 which, when the arm 87 is freed, will restore it to normal position in engagement with the 10 stop 91. In effect there is provided a two-part arm 85, 87, the two parts ordinarily acting as a single rigid member, swinging about the axis 81, but the two parts being yieldably connected so that relative movement may take 15 place between them under certain conditions. The action of the spring 89 is transmitted to the connected parts of the spacing frame, normally maintaining the stop 83 engaged with the stop 82 and tending to restore the 20 space bar after actuation, the downward limit of the space bar being determined by the engagement of the stop 84 with the stationary stop 82. When the space bar is depressed its movement will be transmitted 25 through the levers 79 and rock shaft 81 to the arms 85 and 87, the latter swinging upward and forward and acting against the finger 75 to swing the dog rocker rearward from its 30 normal position and effecting a "reverse" 35 feed.

Under actuation of the printing key levers the escapement mechanism will operate to give the "ordinary" or direct feed. When one of the printing keys 22 is actuated the movement will be transmitted through the described train of connections to the connected type bar 11, swinging the latter from the position of rest to printing position; the type bar after printing returning, together with 40 the actuating mechanism to normal position. As the type bar swings upward towards its printing position the contact face 24, acting against the universal bar 25, will move the latter rearward, rocking the shaft 30 and 45 causing the central arm 31 to move the link 35 rearward, the motion of the link, after its preliminary lost motion, being transmitted through the arm 38 of the dog rocker, swinging the upper end of the rocker forward and 50 causing the middle dog 49 to move forward out of the plane of the escapement wheel. The arm 50 of said dog, as soon as it clears the engaged wheel tooth, will be turned by its spring 55 on the pivot 52 until arrested by 55 contact of the stop 54 with the dog arm 59, when the dog tooth 50 will be behind the previously engaged wheel tooth and in position to engage with the next succeeding wheel tooth as the dog rocker swings back to normal 60 position, permitting the escapement wheel to

turn. As soon as the dog arm 50 has swing forward sufficiently to clear the engaged wheel tooth the forward swing of the rocker will bring the beveled or fixed dog 48 into contact with the rear corner of said tooth, as 65 is shown in Figs. 5 and 6, thus holding the escapement wheel and preventing it from turning until it is released on the return stroke of the dog rocker. When this return stroke has advanced far enough to swing the rigid dog 70 48 clear of the wheel tooth with which it is engaged, the escapement wheel will turn advancing with it the dog 49, the turning movement continuing until the dog arm 50 is arrested by the stop 53. As will be understood 75 this return movement of the dog rocker and the letter space feeding movement of the carriage are dependent on the return movement of the universal bar and its connections to said dog rocker; and the return movement 80 of the universal bar is of course controlled by the type bar, and can take place only during the return movement of the type bar and the upstroke of the connected printing key and key lever. In other words, the escapement 85 operates under the actuation of the printing keys in the usual way of an escapement of the "ordinary" or direct feed style.

During operations of the escapement mechanism under the control of the printing keys the space bar 77 and connected parts up to and including the arm 85 will not be affected, these parts as well as the space bar being independent of the keys 22 and connected devices. When the space bar 90 77 is depressed, the spacing levers 79 will be swung downward until the parts are arrested by the stop 84 contacting with the frame stop 82 and the shaft 81 will be rocked, swinging upward the two-part arm 85, 87 95 and causing the upper end portion of said arm to press upward the arm or extension 75 depending from the dog rocker. As a result the dog rocker will be swung on its pivot, the part below the pivot swinging 100 forward, causing the stop 67 acting against the plunger head 68 to force the plunger forward, compressing the plunger spring; while the upper end of the dog rocker will swing towards the rear, carrying the middle 105 dog 49 out of the escapement wheel and bringing the forward spring mounted pivoted dog 58 into said wheel, the tooth or upper end of the arm 59 entering the plane of the wheel behind the wheel tooth released by 110 the middle dog 49. Consequently as the rearward swing of the dog rocker is continued far enough to carry the middle dog arm 50 clear of said escapement wheel, the latter 115 will turn, bringing the next succeeding wheel tooth into engagement with the dog arm 59 and swinging the latter rightward against the pull of the dog spring 62. The swinging movement of the dog will continue 120 until it is arrested in the position shown in 125 130

Figs. 7 and 8, this arrest being brought about by the engagement of the dog arm 59 with the stop pin 54 and of the stop arm 50 with the stop 53. It will be understood that when the dog arm 50 is released from the wheel it will tend to swing leftward under the impulse of its spring 55 but leftward movement will be prevented by the engagement of the stop pin 54 with the dog arm 59, which, under control of the main spring acting through the escapement wheel tooth, will swing both dog arms 59 and 50 rightward until the dogs are arrested as described. It will be observed that through the depression of the space bar or key 77, the dog rocker has been swung rearward and the dogs 49 and 58 in co-operation with the escapement wheel 6 have effected an advance step or letter feed movement of the carriage, or in other words, that the carriage has been fed or letter spaced through a reverse feeding or full drop action of the escapement mechanism. The dog rocker and escapement wheel will remain related as in Figs. 7 and 8 as long as the space bar 77 is held depressed and provided the printing keys are not operated. Should, however, one of the printing keys be operated at this time the link 35, which maintains constant connection with the dog rocker through the slot 36 and pin 37, will force the lower arm of the dog rocker rearward, causing the extension 75 to act against the arm 87, this arm being forced to yield sufficiently to permit of the escapement mechanism being operated in the ordinary way to give a no-drop escapement, as has been described. In yielding, the arm or lever 87 will swing on the pivot 86 as a center independently of the arm 85, which will remain motionless, the rear portion of the arm 87 swinging down and the spring 89 yielding to permit of this motion. When the actuated printing key is released the arm 87 will be restored to its normal relationship with the arm 85 by the spring 89, and on releasing the key 77 the spacing key and connected mechanism will also be permitted to return to normal position. The described construction permits of a dwelling on or continued holding down of the space bar 77 without obstructing the subsequent operation of one of the printing keys. The actuation of the escapement mechanism under the control of the space bar is independent of the printing mechanism and the universal bar mechanism, the lost motion between the stud 37 and the slot 36 permitting the necessary forward swing of the lower part of the rocker without disturbing the link 35.

Various changes may be made without departing from my invention.

What I claim as new and desire to secure by Letters Patent, is:—

1. In a typewriting machine, the combina-

tion of a traveling carriage, escapement devices comprising a dog carrier and a plurality of dogs thereon, a plurality of keys, and operative connections between said keys and said dog carrier, certain of said keys being effective to operate the escapement devices to give an "ordinary" or direct feed to the carriage on the completion of the movement of the dog carrier, certain other of said keys being effective to operate the escapement devices to give a reverse or full drop feed to the carriage during the excursion of the dog rocker in one direction and before the start of its return movement. 70 75

2. Escapement mechanism for typewriter machines, comprising an escapement dog carrier provided with three dogs in combination with key operated means for changing the character of the escapement by changing the direction of movement of the dog carrier so as to dispense with the use of certain of said dogs in favor of certain other of said dogs. 80 85

3. In a typewriting machine, the combination of a traveling carriage, escapement devices comprising a vibratory dog carrier, printing keys, and a space key, the printing keys being effective to operate said escapement devices as an "ordinary" or direct feed escapement during the second half of the vibration of said dog carrier and the space key being effective to operate said escapement devices as a reverse or full drop escapement during the first half of the vibration of said dog carrier. 90 95 100

4. In a typewriting machine, the combination of a traveling platen carriage, type bars co-operative with the platen, escapement devices comprising a vibratory dog carrier, and a plurality of keys, certain of said keys being effective both to actuate the type bars and also to operate the escapement devices as an "ordinary" or direct feed escapement during the second half of the vibration of said dog carrier and certain other of said keys being independent of all of the type bars but being effective to operate the escapement devices as a reverse or full drop escapement during the first half of the vibration of said dog carrier. 105 110 115

5. In a typewriting machine, the combination of a traveling carriage, escapement devices, a universal bar connected to certain of said devices, keys operative on said universal bar to actuate said devices in one direction to give an "ordinary" or direct feed to the carriage, and a key operative independently of said universal bar to actuate said certain devices initially in the opposite direction to give a reverse feed to the carriage. 120 125

6. In a typewriting machine, the combination of a traveling carriage, escapement devices comprising a dog rocker, a plurality of keys, certain of said keys being effective to actuate said dog rocker in one direction 130

- from normal position to give an "ordinary" or direct feed, and certain of said keys being effective to actuate said dog carrier in the opposite direction from normal position 5 to give a reverse feed.
7. Escapement mechanism for typewriting machines comprising a key actuated dog carrier operative in opposite directions from a single normal position to vary the character 10 of the escapement.
8. Escapement mechanism for typewriting machines comprising the comb of a dog carrier and key actuated means for operating it in opposite directions from a single 15 normal position to vary the character of the escapement, the movement of said dog carrier in one direction from normal giving the "ordinary" feed and movement in the opposite direction from normal giving a "reverse" 20 feed.
9. Escapement mechanism for typewriting machines comprising a key actuated dog carrier operative in opposite directions from a single normal position to vary the character 25 of the escapement, the movement of said dog carrier in one direction from normal under actuation of the printing keys giving the "ordinary" feed and movement in the opposite direction from normal under actuation 30 of the space key giving a "reverse" feed.
10. In a typewriting machine, the combination of a traveling carriage, escapement devices comprising a dog carrier, a universal bar operative on said dog carrier, key 35 actuated type bars, said type bars being operative on said universal bar to move said dog carrier in one direction, a space bar, and connections operated by said space bar for moving said dog carrier in the opposite direction.
11. In escapement mechanism for typewriting machines comprising an escapement rack, three escapement dogs or detents having an unvarying normal relationship 45 with said rack and means for selectively operating said dogs to vary the character of the escapement.
12. In combination with the printing keys and space bar of a typewriting machine, escapement devices comprising a plurality of dogs, and devices for selectively controlling said dogs to vary the character of the escapement, the printing keys causing certain 55 of said dogs to co-operate with the escapement rack and the space bar also causing certain of said dogs to co-operate with said rack.
13. In combination with the printing keys and space bar of a typewriting machine, escapement devices comprising a plurality of dogs, and devices for selectively controlling said dogs to vary the character of the escapement, the printing keys causing certain 60 of said dogs to co-operate with the escapement rack and the space bar also causing certain of said dogs to co-operate with said rack.
- certain of said dogs to co-operate with said rack, one of the dogs controlled by the space bar being inoperative by the printing keys and one of the dogs controlled by the printing keys being inoperative by the space bar. 70
14. In a typewriting machine, the combination of a traveling carriage, an escapement rack, a dog carrier, a dog thereon, means for controlling the carriage to maintain said dog normally engaged with said rack, two other dogs having an unvarying relationship with each other and with said first recited dog, and means for selectively causing co-operation between said other dogs and the escapement rack to vary the character 75 of the escapement.
15. In a typewriting machine, the combination of a traveling carriage, an escapement rack, a dog carrier, a dog thereon, means for controlling said dog carrier to maintain said dog normally engaged with said rack, two other dogs having an unvarying relationship with each other and with said first recited dog, and means for selectively causing co-operation between said other dogs 80 and the escapement rack to vary the character of the escapement, one of said other dogs co-operating with the normally engaged dog and the escapement rack to give an "ordinary" feed and the second of said other 85 dogs co-operating with the normally engaged dog and the escapement rack to give a reverse feed.
16. In a typewriting machine, the combination of printing keys, a space key, a traveling carriage, an escapement rack, a dog carrier, a dog thereon, means for controlling the carriage to maintain said dog normally engaged with said rack, two other dogs having an unvarying relationship with 90 each other and with said first recited dog, and means for selectively causing co-operation between said other dogs and the escapement rack to vary the character of the escapement, one of said other dogs co-operating 95 with the normally engaged dog under actuation of the printing keys and with the escapement rack to give an "ordinary" feed, and the second of said other dogs co-operating with the normally engaged dog under actuation of the printing keys and with the escapement rack to give a reverse feed. 100
17. In a typewriting machine, the combination of a traveling carriage, an escapement rack, a dog rocker, three dogs mounted on said rocker and having an unvarying normal position thereon, means for maintaining the rocker so that one of said dogs is constantly normally engaged with said escapement rack, and key controlled means for 110 operating said rocker to selectively render said dogs operative in connection with the normally engaged dog to determine the character of the escapement.
18. In a typewriting machine, the combination of a traveling carriage, an escapement rack, a dog carrier, a dog thereon, means for controlling the carriage to maintain said dog normally engaged with said rack, two other dogs having an unvarying relationship with each other and with said first recited dog, and means for selectively causing co-operation between said other dogs and the escapement rack to vary the character of the escapement. 115
19. In a typewriting machine, the combination of a traveling carriage, an escapement rack, a dog carrier, a dog thereon, means for controlling said dog carrier to maintain said dog normally engaged with said rack, two other dogs having an unvarying relationship with each other and with said first recited dog, and means for selectively causing co-operation between said other dogs and the escapement rack to vary the character of the escapement. 120
20. In a typewriting machine, the combination of a traveling carriage, an escapement rack, a dog carrier, a dog thereon, means for controlling the carriage to maintain said dog normally engaged with said rack, two other dogs having an unvarying relationship with each other and with said first recited dog, and means for selectively causing co-operation between said other dogs and the escapement rack to vary the character of the escapement. 125
21. In a typewriting machine, the combination of a traveling carriage, an escapement rack, a dog carrier, a dog thereon, means for controlling said dog carrier to maintain said dog normally engaged with said rack, two other dogs having an unvarying relationship with each other and with said first recited dog, and means for selectively causing co-operation between said other dogs and the escapement rack to vary the character of the escapement. 130

- nation of a traveling carriage, an escapement rack, a dog rocker, three dogs mounted on said rocker, means for maintaining the rocker so that one of said dogs is constantly normally engaged with said escapement rack, and key controlled means for operating said rocker to selectively render the other two dogs operative in connection with the normally engaged dog to determine the character of the escapement, the said other two dogs being normally disengaged and at opposite sides of the plane of the escapement rack, said rocker being swingable oppositely from its central normal position to bring one or the other of said normally disengaged dogs into use.
19. In a typewriting machine, the combination of a traveling carriage, an escapement rack, a dog carrier, a holding dog thereon, two feed dogs also on said carrier, all of said dogs having an unvarying normal relationship with each other and with said rack, and means for causing selective co-operation of said dogs with said rack.
20. In a typewriting machine, the combination of a traveling carriage, an escapement rack, a dog carrier, a holding dog thereon, feed dogs arranged on said carrier, and means for moving said carrier oppositely to cause co-operation of one feed dog or alternatively of the holding dog with said rack.
21. In a typewriting machine, the combination of a traveling carriage, an escapement rack, a pivoted dog rocker, a feed dog pivotally supported on said rocker and normally engaging said escapement rack, a holding dog rigidly mounted on said rocker at one side of said feed dog, a second feed dog mounted at the opposite side of the first recited feed dog on said rocker, and means for oppositely swinging said rocker to cause alternative cooperation of said holding dog and of said second feed dog with said escapement rack.
22. In a typewriting machine, the combination of a traveling carriage, an escapement rack, a pivoted dog rocker, a feed dog pivotally supported on said rocker and normally engaging said escapement rack, a holding dog rigidly mounted on said rocker at one side of said feed dog, a second feed dog mounted at the opposite side of the first recited feed dog on said rocker, printing keys, operative on said rocker and a space key operative to swing said rocker oppositely from said printing keys.
23. In an escapement mechanism for typewriting machines, the combination of an escapement wheel, a pivoted dog rocker, a spring mounted feed dog arranged on said rocker and normally engaging with said escapement wheel, a second spring mounted dog on said rocker, a holding dog rigidly mounted on said rocker, said holding dog and said second spring mounted dog being arranged at opposite sides of the plane of the escapement wheel, and means for oppositely swinging said dog rocker to cause alternative co-operation with the escapement wheel of said second spring mounted dog and of said holding dog.
24. In an escapement mechanism for typewriting machines, the combination of an escapement wheel, a pivoted rocker, a spring mounted feed dog thereon normally engaging with said escapement wheel, a second spring mounted dog on said rocker, a holding dog rigidly mounted on said rocker, said holding dog and said second spring mounted dog having engaging portions at opposite sides of the first named feed dog, and means for oppositely swinging said dog rocker to cause alternative co-operation with the escapement wheel of said second spring mounted dog and said holding dog, said means comprising printing keys and connections and a space bar and connections.
25. In an escapement mechanism for typewriting machines comprising an escapement wheel connected with the traveling carriage of the machine, a pivoted dog rocker, two co-axially pivoted dogs on said rocker, spring means constantly acting on said dogs, a holding dog rigid on said rocker, and means for actuating said rocker to cause selective co-operation of said dogs with said rocker.
26. In an escapement mechanism for typewriting machines comprising an escapement wheel connected with the traveling carriage of the machine, a pivoted dog rocker, two co-axially mounted spring pressed dogs on said rocker, a holding dog rigid on said rocker, and means for actuating said rocker to cause selective co-operation of said dogs with said rocker, the holding dog being rendered effective by the printing keys of the machine, and one of the pivoted dogs being rendered effective by the space key of the machine, the other pivoted dog normally co-operating with the escapement wheel.
27. In a typewriting machine, the combination of a carriage, an escapement rack, an escapement dog carrier, a plurality of escapement dogs thereon having a constant normal relationship both to said dog carrier and to said rack, and key operated means for changing the character of the escapement by changing the initial direction of movement of said dog carrier.
28. In combination with the printing keys and space bar of a typewriting machine, escapement devices comprising a plurality of dogs and devices for selectively controlling said dogs to vary the character of the escapement, the space bar of the machine causing certain of said dogs during the initial stage of their movement to co-operate with the escapement rack to cause a "reverse" feed during the depression of the space key, any printing key being effective to actuate the

escapement mechanism while the space key is maintained depressed.

29. In combination with the printing keys and space bar of a typewriting machine, escapement devices comprising a plurality of dogs and devices for selectively controlling said dogs to vary the character of the escapement, the space bar of the machine causing certain of said dogs during the initial stage of their movement to co-operate with the escapement rack to cause a "reverse" feed during the depression of the space key, any printing key being effective to actuate the escapement mechanism while the space key is maintained depressed, the printing keys normally operating to cause step by step feeding movements of the carriage during return strokes of said printing keys.

30. In a typewriting machine, the combination of a traveling carriage, an escapement rack, a dog carrier, escapement dogs thereon, spring controlled means normally maintaining said dog carrier in a predetermined normal position, and key operated means for overcoming said spring controlled means to move said dog carrier in opposite directions from its normal position.

31. In a typewriting machine, the combination of a traveling carriage, an escapement rack, a dog carrier, escapement dogs thereon, a carrier spring constantly tending to move said carrier in one direction, a stronger spring effective to limit the action of said carrier spring, and means for overcoming said stronger spring.

32. In a typewriting machine, the combination of a traveling carriage, an escapement rack, a dog carrier, escapement dogs thereon, a carrier spring constantly tending to move said carrier in one direction, a stronger spring effective to limit the action of said carrier spring, and means for overcoming said stronger spring comprising a space key and connections to said dog carrier.

45 33. In a typewriting machine, the combination of a traveling carriage, an escapement rack, a dog carrier, escapement dogs thereon, a carrier spring constantly tending to move said carrier in one direction, a stop on said carrier, a co-operative spring plunger stop acting normally to arrest the movement of the carrier under the action of said carrier spring, and means operative on said carrier to overcome said spring plunger stop.

55 34. In a typewriting machine, the combination of a traveling carriage, an escapement rack, a dog carrier, escapement dogs thereon, a carrier spring constantly tending to move said carrier in one direction, a stop on said carrier, a co-operative spring plunger stop acting normally to hold the carrier against movement under the action of said carrier spring, and means operative on said carrier to overcome said spring plunger

stop, said means comprising a spacing frame, an arm operative by said frame, and a co-operating arm on the dog carrier.

35. Escapement mechanism for typewriting machines comprising a key actuated dog carrier, oppositely movable from normal position to vary the character of the escapement, a key actuated universal bar for moving the carrier in one direction, a space bar, and connections between said space bar and said carrier comprising a yieldable member, said member when the space bar is held depressed yielding in order to permit operation of said dog carrier from the universal bar.

36. Escapement mechanism for typewriting machines comprising a key actuated dog carrier oppositely movable from normal position to vary the character of the escapement, a key actuated universal bar for moving the carrier in one direction, a space bar, a rock shaft to which said space bar is connected, an arm fixed to said rock shaft, an arm or lever pivoted on said first recited arm, stop means limiting the movement of said arm or lever, a spring connected to said arm or lever, and a device connected to said dog carrier with which said arm or lever co-operates.

37. In a typewriting machine, the combination of a carriage escapement mechanism therefor comprising a dog carrier, a key actuated universal bar for moving the carrier in one direction, a space bar, spacing levers to which said space bar is connected, a rock shaft on which said levers are supported, a two-part member supported on said rock shaft comprising a spring pressed lever, and a projection on said dog carrier with which said lever is adapted to co-operate to move said carrier oppositely from the direction in which it is moved by the universal bar.

38. In escapement mechanism for typewriting machines, the combination of a dog carrier, a key actuated universal bar for moving the carrier in one direction, a space bar, spacing levers to which said space bar is connected, a rock shaft on which said levers are supported, an arm fixed to said rock shaft, a spring mounted lever supported by said arm, and a projection on said dog carrier with which said spring mounted lever is adapted to co-operate, said spring mounted lever yielding under operation of the dog carrier by the universal bar when the space bar is maintained depressed.

Signed at the borough of Manhattan, city of New York, in the county of New York and State of New York, this 31st day of August A. D. 1920.
